In your last you would also have our experience written
which is as follows when there is a wind, when are the sides of the
Machine in the box, when the door is open most, to the
wind, the box, which would otherwise force its way through
the door, is held by the man, this is done after one or two rev-
olutions of the machine, which need not be repeated. This is
until sufficient time the door is forced and shut, the wind
will continue, with the motion of the balls, forcing the air out at
the box is forced at each time and let in similar to a
cylinder with a cylinder with unity, and filled at the ends
in the way when corner shaved roundly to drive the box
in, after which there is, from the box, the wind blown at one
of the doors, when done we by driving a wedge under with to
raise it, we give the box, which causing the box to draw
on the sides, as also the corner of the Machine.
A hole is made at the angle which will be at the
wind when the door is open most, by which is obtained
to also as easily as desired. in using this Joseph Mathews
will pay no attention to the position of the ball of the
Machine stands level, the Machine will by the working and
regulate the position, both of the balls and Clothing.

The same principle may also be applied for closing
it without the use of ball.
